UNITED STATES PATENT OFFICE

154,270

DESIGN FOR A HOLDER FOR BROOMS OR THE LIKE

Clarence Lewis Hawn, St. Paul, Minn.

Application July 21, 1947, Serial No. 140,410

Term of patent 14 years

(Cl. D9—2)

To all whom it may concern:

Be it known that I, Clarence L. Hawn, a citizen of the United States, residing at 1651 Marshall Avenue, St. Paul, Minnesota, have invented a new, original, and ornamental Design for a Holder for Brooms or the like, of which the following is a specification, reference being had to the accompanying drawing, forming a part thereof.

In the drawing:

Fig. 1 is a perspective view of a holder for brooms or the like showing my new design;

Fig. 2 is a plan view of the same;

Fig. 3 is a front elevational view of the same, and

Fig. 4 is a left-hand end elevational view of Fig. 3.

I claim:

The ornamental design for a holder for brooms or the like, as shown.

CLARENCE LEWIS HAWN.
